UNITED STATES PATENT OFFICE.

GEORGE T. CULL, OF WICKLIFFE, KENTUCKY.

BRUSH AND SPOON HOLDER.

1,202,676.

Specification of Letters Patent.

Patented Oct. 24, 1916.

Application filed April 21, 1915. Serial No. 22,832.

To all whom it may concern:

Be it known that I, GEORGE T. CULL, a citizen of the United States, residing at Wickliffe, in the county of Ballard and State of Kentucky, have invented certain new and useful Improvements in Brush and Spoon Holders; and I do hereby declare the following to be a full, clear, and exact description of the invention, such as will enable others skilled in the art to which it appertains to make and use the same.

This invention relates to new and useful improvements in brush and spoon holders and the principal object of the invention is to provide a device which is readily attachable to stew pans, paint cans and the like for supporting spoons and brushes out of the can and in such condition that their bowls or bristles will be supported over the receptacle.

Another object of the invention is to provide a device which is readily constructed of sheet metal and capable of being secured to stew pans or cans of the ordinary construction without in any way changing the same.

Still another object of the invention is to provide a device which may be riveted to the receptacle on which it is used.

A still further object of the invention is to provide a device which is capable of being formed integral with the side wall of the receptacle and which will support the brush or spoon when the same is not in use.

With these and other objects in view, the invention consists in the novel combination and arrangement of parts which will be fully set forth in the following specification and accompanying drawings, in which:

Figure 1 is a plan view of the blank from which my improved holder is constructed. Fig. 2 is a sectional view through a portion of a receptacle showing the spoon holder in place. Fig. 3 is an end view of the spoon holder. Fig. 4 is an end view of a modified form of the device, and Fig. 5 is a detail perspective view of the attachment which may be riveted or otherwise secured to the side of a can or receptacle.

Referring to the drawings by characters of reference, the numeral 1 designates as an entirety the blank from which my improved spoon holder is constructed which comprises the body 2 formed with the arcuate slits 3, which slits extend longitudinally of the body and are arranged so that their convex portions are adjacent. The portion between

the slits is designated by the numeral 4 and arranged to be bent on the fold lines 5 and the fold line 6 which is arranged intermediate its ends. Formed at each end of the body 2 are the tongues 7 which coöperate with each other in supporting the device on the edge of a receptacle. These tongues 7 form clamp jaws which are joined by the body 2 and the portion 4 between the slits 3 when the device is in its folded position extends as shown in Fig. 2 and forms a supporting shelf for the spoon handle. Due to the inclination of the slits 3 it will be evident that the spoon may be moved so that the same cannot be accidentally dislodged and it will remain in position on the edge of the receptacle.

In the modified form of the invention, the body 2 is slightly enlarged as at 8 and the slits 3 are so widely spaced from each other as to receive the handle of a paint brush and it will be seen that when this device is in use a paint brush may be supported so that its bristles overhang the can.

In Fig. 5 is a further modification of the invention which comprises the plate 9 having formed thereon the tapered end 10 which is provided with the inwardly inclined slits 11 forming the arms 12 and the tapered tongue 13. This tongue 13 is bent angularly as illustrated and the body 9 is provided with a pair of spaced openings 14 for the reception of rivets or the like. In event that it is desired to construct this spoon holder integral with the side wall of a receptacle, a portion thereof is extended upwardly and provided with suitable slits and the whole is constructed in a manner similar to the modification illustrated in Fig. 5.

It will be apparent from the foregoing that in use the device is first bent in the position illustrated in Figs. 2 and 3 and the portions 7 may then be slipped over the edge of the receptacle and the device is ready for service. Upon laying a spoon across the portion 4, it will be evident that the same will be supported and if it is moved so that the wider portion engages the inclined faces of the portions 2, it will be apparent that the spoon will not be accidentally dislodged. The modification illustrated in Fig. 4 is used in a similar manner only that in place of the spoon, the usual paint brush or the like is supported.

While in the foregoing there has been

shown and described the preferred embodiment of this invention, it is to be understood that such changes may be made in the combination and arrangement of parts as 5 will fall within the spirit and scope of the appended claims.

What is claimed is:—

A holder of the character described constructed of a single piece of sheet metal having outwardly and oppositely curved slits, 10 the holder being bent centrally to provide a

pair of gripping members, and the portion lying between the slits being collapsed and directed laterally to provide a support for an article inserted between the outwardly 15 converging edges of the slits.

In testimony whereof I affix my signature in presence of two witnesses.

GEORGE T. CULL.
